EDWARD H. RIPLEY, OF BOSTON HIGHLANDS, MASSACHUSETTS, ASSIGNOR
TO HIMSELF AND JOHN A. KOHL, OF SAME PLACE.

Letters Patent No. 96,965, dated November 16, 1869.

IMPROVED ALARM FOR LETTER-BOXES.

The Schedule referred to in these Letters Patent and making part of the same.

To all whom it may concern:

Be it known that I, EDWARD H. RIPLEY, of Boston Highlands, in the county of Suffolk, and State of Massachusetts, have invented a new and useful Improvement in Letter-Carriers' Alarm; and I do hereby declare that the following is a full, clear, and exact description thereof, which will enable others skilled in the art to make and use the same, reference being had to the accompanying drawings, forming part of this specification, in which—

Figure 1 is a front or outside view of a portion of a door to which my improvement has been attached.

Figure 2 is a vertical detail section of the same, taken through the line *x x*, fig. 1.

Figure 3 is an inside view of the same, part of the bell being cut away through the line *y y*, fig. 2.

Similar letters of reference indicate corresponding parts.

My invention has for its object to furnish an improved attachment for the doors of houses, offices, &c., which are kept constantly or occasionally locked or bolted, which shall be so constructed and arranged as to enable the letter-carrier to pass letters and other small packages through said door, and, at the same time, will notify the inmates of their delivery; and

It consists in the construction and combination of the various parts of the apparatus as hereinafter more fully described.

A represents the door of a house, office, or other building, where mail-matter is to be delivered.

In a convenient part of the door *A*, is formed a slit, *a'*, inclining downward, as it passes inward, and which may be protected, upon the outer and inner side, either or both, with slotted plates.

B is a plate, having the number of the house or office, or the name of the occupant, placed upon it, and which is provided with a knob, or other handle, for operating it.

The plate *B* is made of such a size as to cover the slit in the door, and is securely attached to the outer end of the spindle *C*, which passes in through the

door *A*, and upon the inner end of which is placed a coiled spring, *D*, one end of which is attached to the end of the said spindle, and its other end rests against, or is connected with a stop-pin, attached to the door *A*, or to the plate placed upon the inner side of said door.

The spring *D* serves the double purpose of holding the plate *B* down to its bearings, to prevent the ingress of rain, and to bring the plate *B*, when released by the operator, back to its place, covering the said slit in the door *A*.

To the inner part of the spindle *C*, is attached a dog or tumbler, *E*, having an arm formed upon it, which, by striking against stops attached to the inner side of the door, or to the plate attached to said door, limits the movement of the plate *B*.

The dog or tumbler *E* has two notches formed in its edge, upon which the catch of the spring-catch *F* catches.

The other end of the spring-catch *F* is attached to the spring-hammer arm *G*, which sounds the alarm, by striking the bell *H* twice, as the spring-catch *F* is released successively from the two notches of the tumbler *E*.

Having thus described my invention,

I claim as new and desire to secure by Letters Patent—

1. The pivoted plate *B*, and rotating spindle *C*, for covering the slit in the door, and for operating the alarm-mechanism, substantially as herein shown and described.

2. The combination of the pivoted plate *B*, rotating-spindle *C*, coiled spring *D*, dog or tumbler *E*, spring-catch *F*, spring-hammer *G*, and bell *H*, with each other, substantially as herein shown and described, and for the purpose set forth.

EDWARD H. RIPLEY.
